United States Patent Office

Des. 193,262
Patented July 24, 1962

193,262

SIGN

Fred G. Owles, Jr., Orlando, Fla., assignor to
George H. Rackensperger, Winter Park, Fla.

Filed Feb. 26, 1962, Ser. No. 68,967

Term of patent 14 years

(Cl. D1—12)

FIG. 1

FIG. 3

I claim:

The ornamental design for a sign, as shown and described.
